AUTOMOBILE BRAKE

Filed June 18, 1928

FIG. 1.

FIG. 2. INVENTOR

JAMES BUTLER.

BY J. L. STEPHENSON

ATTORNEYS.

UNITED STATES PATENT OFFICE.

JAMES BUTLER, OF HARRIETSVILLE, ONTARIO, CANADA.

AUTOMOBILE BRAKE.

Application filed June 18, 1928. Serial No. 286,433.

My invention relates to improvements in automobile brakes, and the object of the invention is to devise a brake of this type, in which the wear of the shoes will be distributed evenly from end to end, thereby increasing the life of the shoe, and at the same time providing a more effective and positive grip upon the brake drum when the shoes are forced into contact therewith, and it consists essentially of the arrangement and construction of parts as herein-after more particularly explained.

Fig. 1 is a face sectional view on line 1—1 Fig. 2.

Fig. 2 is a transverse sectional view through the centre of Fig. 1.

In the drawing like characters of reference indicate corresponding parts in each figure.

20 1 indicates the brake drum of any usual construction, and 2 the disc carried by the axle and from which the axle arm 3 extends in the usual manner. The disc 2 is provided with a peripheral recess 3^x for a purpose which will hereinafter appear.

25 5 and 5^x are parallel guides secured to the inner face of the disc and between which is slidably mounted a slide plate 6 having a slotted opening 7 through which the axle arm 3 extends. 8 is an arm extending from the plate 6 and provided with an offset portion 9 extending through the recess 3^x so as to avoid the brake drum 1 as will be clearly seen on reference to Fig. 2.

30 10 and 11 are the brake shoes mounted to move diametrically of the disc 2 between the guides 10^x and 10° and 11^x and 11°.

When a horizontal movement is imparted to the plate 6 between the guides 5 and 5^x the brake shoes 10 and 11 are moved at right angles to the line of movement of the plate 6, such shoes being moved bodily parallel to this line of direction by means of the following mechanism which I will now describe.

35 13 and 14 are links pivotally connected to the shoe 10 at 13^x and 14^x, and 15 and 16 are links pivotally connected at 15^x and 16^x to the shoe 11. 17 and 18 are bell cranks pivoted at 17^x and 18^x to the disc 2, and 19

and 20 are bell cranks pivoted at 19^x and 20^x also to the disc 2.

The long arms of the bell crank 17 and 18 are pivoted at 17° and 18° to the slide plate 6 and the long arms of the bell cranks 19 and 20 are pivoted at 19° and 20° to the opposite side of the slide plate 6.

The short arms of the bell cranks 17 and 18 are pivotally connected at 21 and 22 to the inner ends of the links 13 and 14, and 60 the short arms of the bell cranks 19 and 20 at 23 and 24 to the inner ends of the links 15 and 16.

It will thus be seen that when the plate 6 is drawn in the direction of arrow, the short 65 arms of the bell cranks 17 and 18, 19 and 20 will be swung outward simultaneously carrying the links 13 and 14, 15 and 16 in a corresponding direction and each end of the shoes to which they are connected evenly 70 and parallel to the vertical centre line of the brake into contact with the inner periphery of the brake drum, such contact being even from end to end of each shoe, and thereby distributing the wear on the shoes 75 so that they will not be worn unequally and thereby quickly lose their usefulness.

It will also be seen by my construction the whole surface of the shoe is carried into gripping contact with the brake drum so as 80 to thereby provide a maximum gripping effect between the shoes and the drum.

What I claim as my invention:—

In an automobile brake, the combination with the brake drum and axle disc having 85 a slotted opening at its periphery, of a slide plate mounted upon the inner face of the disc to move diametrically, means extending through the slotted opening of the disc for operating the plate, brake shoes arranged at 90 opposite points at each side of the plate, guides between which the brake shoes move, links connected to the shoes at each end thereof, a bell crank corresponding to each link pivotally mounted upon the disc, and 95 a pivotal connection between one arm of the bell crank and its corresponding link, and a pivotal connection between the other arm of the bell crank and the plate.

JAMES BUTLER.
